UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR A DRESS

Application filed August 27, 1930. Serial No. 36,810. Term of patent 3½ years.

To all whom it may concern:

Be it known that I, DOROTHY LONG, a citizen of the United States and a resident of New York city, borough of Manhattan, in the county of New York and State of New York, have invented the new, original, and ornamental Design for Dress, of which the following is a specification.

Reference is had to the accompanying drawing forming part thereof, wherein—

tive view of the dress showing my new design, the same being illustrated on a figure partially indicated by dotted lines;

Figure 2 is a three-fourths rear perspective view of the dress shown in Figure 1, the same being illustrated on a figure partially indicated by dotted lines.

I claim—

The ornamental design for a dress substantially as shown and described.

DOROTHY LONG.
